(57) **CLAIM**

The ornamental design for pair of front side illumination sconces for a community communication hub kiosk, as shown and described.

DESCRIPTION

FIG. 1 is a perspective view showing the design of pair of front side illumination sconces for a community communication hub kiosk of the present invention;

FIG. 2 is a front side view thereof;

FIG. 3 is a right view thereof;

FIG. 4 is a left side view thereof; and,

FIG. 5 is a top plan view thereof.

The broken lines showing in FIGS. 1-5 are for illustrative purposes only and do not form part of the claimed design.
